UNITED STATES PATENT OFFICE

146,735

DESIGN FOR A SLIPPER

Thelma M. Carpenter, Brentwood, Pa.

Application May 11, 1946, Serial No. 129,601

Term of patent 7 years

(Cl. D7—7)

To all whom it may concern:

Be it known that I, Thelma M. Carpenter, a citizen of the United States, residing at Brentwood, Pittsburgh 27, in the county of Allegheny and State of Pennsylvania, have invented a new, original, and ornamental Design for Slipper, of which the following is a specification, reference being had to the accompanying drawing, forming part thereof.

The figure is a perspective view of a slipper, showing my new design.

I claim:

The ornamental design for a slipper, as shown.
THELMA M. CARPENTER.
